CLAIM

The ornamental design for a hand-held electric hair
dryer, substantially as shown and described.

DESCRIPTION

FIG. 1 is a perspective view of the front and right side
of a hand-held electric dryer showing my new design;
FIG. 2 is a top plan view of the dryer of FIG. 1;
FIG. 3 is a bottom plan view of the dryer of FIG. 1;
FIG. 4 is an elevational view of the front of the dryer of
FIG. 1;

FIG. 5 is an elevational view of the right side of the
dryer of FIG. 1;

FIG. 6 is an elevational view of the rear of the dryer of
FIG. 1; and

FIG. 7 is an elevational view of the left side of the dryer
of FIG. 1.

The cord is shown only partially for convenience of
illustration.
